US00D860790S

(12) **United States Design Patent** (10) **Patent No.:** **US D860,790 S**
(45) **Date of Patent:** **** Sep. 24, 2019**

(54) **STACKABLE FOOD HOLDER**

(71) Applicant: **Inno-Pak, LLC**, Delaware, OH (US)

(72) Inventor: **Nathan Sedgwick**, Aliso Viejo, CA
(US)

(73) Assignee: **Inno-Pak, LLC**, Delaware, OH (US)

(**) Term: **15 Years**

(21) Appl. No.: **29/618,759**

(22) Filed: **Sep. 23, 2017**

(51) **LOC (12) Cl.** **09-07**

(52) **U.S. Cl.**

USPC **D9/456**

(57) **CLAIM**

The ornamental design for a stackable food holder, as shown.

DESCRIPTION

FIG. 1 is a front perspective view of the stackable food holder of the present invention;

FIG. 2 is a top plan view thereof;

FIG. 3 is a side view thereof, as shown from the rear side of FIG. 2;

FIG. 4 is a side view thereof, as shown from the front side of FIG. 2;

FIG. 5 is a side view thereof, as shown from the left side of FIG. 2; and,

(Continued)

FIG. 6 is a side view thereof, as shown from the right side of FIG. 2.

1 Claim, 4 Drawing Sheets
